Specification for Design.

Patented Aug. 21, 1917.

Application filed April 26, 1917. Serial No. 164,812. Term of patent 14 years.

To all whom it may concern:

Be it known that I, LÉON DUFOUR, a citizen of Switzerland, residing at Geneva, in the Canton of Geneva, Switzerland, have invented a new, original, and ornamental Design for Radiators for Motor-Cars, of which the following is a specification, reference being had to the accompanying drawing, forming part thereof.

In the drawing:

Figure 1 is a side elevation of a radiator

for a motor car illustrating my new design, and

Fig. 2 is a front elevation of the same.

I claim:

The ornamental design for a radiator for motor cars as shown.

In testimony whereof I have affixed my signature.

LÉON DUFOUR.
